COMBINED PISTON RESIZER AND MOTOR SUPPORT

John A. Riordan, Denver, Colo.

Application January 2, 1953, Serial No. 22,979

Term of patent 7 years

(Cl. D54—13)

To all whom it may concern:

Be it known that I, John A. Riordan, a citizen of the United States, residing at Denver, State of Colorado, have invented a new, original, and ornamental Design for a Combined Piston Resizer and Motor Support, of which the following is a specification, reference being had to the accompanying drawing, forming a part hereof.

Fig. 1 is a top plan view of a combined piston resizer and motor support, showing my new design.

Fig. 2 is a side elevational view thereof, the opposite side being identical therewith except that it will be reversed.

Fig. 3 is a bottom plan view looking upwardly in Figure 2; and

Fig. 4 is an end elevational view looking towards the left of Figure 2.

I claim:

The ornamental design for a combined piston resizer and motor support, as shown and described.

JOHN A. RIORDAN.
